ALIGNING BRACKET FOR ACCORDION DOOR

Paul H. Nelson, Plainville, Conn., assignor to The Stanley Works, New Britain, Conn., a corporation of Connecticut

Application January 14, 1957, Serial No. 634,081

3 Claims. (Cl. 16—1)

This invention relates to folding doors and more particularly to a novel and improved means for aligning the lower edge of the end panel of such a door of the type wherein the lower edge of the door is unguided.

It is the object of this invention to provide a novel and improved means for aligning the lower free edge of the end panel of a wooden folding door with the door opening as the door is being closed so as to correct any misalignment of the door and door opening due to warping of the door; and which will maintain the lower free edge of the end panel in alignment with the door opening when the door is closed.

Other objects will be in part obvious, and in part pointed out more in detail hereinafter.

The invention accordingly consists in the features of construction, combination of elements and arrangement of parts which will be exemplified in the construction hereafter set forth and the scope of the application of which will be indicated in the appended claims.

In the drawings:

Fig. 1 is an elevational view of a pair of folding doors mounted in a door opening with a pair of aligning brackets constructed in accordance with the invention mounted respectively on the end panels of the doors;

Fig. 2 is an enlarged fragmentary cross sectional view substantially on the line 2—2 of Fig. 1;

Fig. 3 is an enlarged perspective view of one of the aligning brackets; and

Fig. 4 is an enlarged fragmentary cross sectional view of the doors of Fig. 1 illustrating the operation of the aligning brackets.

While the aligning brackets which form the subject of this invention have been shown in the drawing respectively mounted on the adjoining end panels of a pair of folding doors, it will be apparent from the subsequent description that the brackets are equally useful in aligning the end panel of a single door with the side of a door opening. In order to correlate the latter use of the brackets with the subsequent description, the end vertical edge of one of the doors shown in the drawing, when the door is in the aligned closed position of Figs. 1 and 2, may be considered as a side of the door opening.

The folding doors shown in Fig. 1 each generally comprise wood panels 10 and 11, hingedly connected along one edge at 12. The inner panels 10 are pivotally mounted in the door frame as at 13 and 14. A guide 15 is mounted adjacent the outer end of the top of the end panels 11 and is engaged by a guide track 16 mounted at the top of the door opening and in alignment therewith. As can be seen, no guide track and guide arrangement is provided for the bottom of the door inasmuch as it is not desired to provide any obstruction along the floor which could cause a person to trip while passing through the door opening.

As is evident, warping of the wooden panels of the door may undesirably cause the lower free edge of the

2

doors to be displaced out of alignment with the door opening when the door is in the closed position of Fig. 1. In order to prevent such misalignment of the doors and door opening, a pair of aligning brackets 18 and 20 are respectively mounted on the faces of the adjoining end panels of the doors. Inasmuch as the brackets are identical in structure, in the interest of brevity only the bracket 18 will be described in detail.

The bracket 18, in accordance with the invention, 10 comprises a flat base 22. A flat guide arm 24 extends outwardly at an acute angle from one edge of the base and a second flat guide arm 26, vertically spaced relatively to the arm 24, extends angularly of the arm 24 inwardly from said one edge of the base at an angle thereto corresponding generally to that of the arm 24.

In the preferred embodiment, the arm 26 is substantially shorter than the arm 24 so as not to unduly interfere with the full opening of the end panels 11, inasmuch as when the door is fully opened the arm 26 will engage the face of the panel 10. A pair of elongated apertures 28 are provided on the base for the mounting of the bracket on a panel and to permit adjustment of the bracket relative to the panel. In the specific embodiment the bracket is fabricated from a single piece 20 of sheet metal providing an economical and easily fabricated structure.

In use, the brackets are mounted on the faces of the end panels, as shown, with one bracket inverted relative to the other. The doors are then closed with the bottoms thereof aligned with the door openings; and with the doors so aligned the brackets are adjusted relative to each other and to the door to bring the outwardly extending arm 24 of each bracket into firm lapping engagement with the inwardly extending arm 26 of the other bracket, as most clearly shown in Fig. 2, to exert an endwise force on the doors. With the brackets engaged, as described, any warpage of either of the end panels 11 tending to displace the panel relative to the adjoining end panels and the door opening will be prevented; for example, displacement of the righthand panel 11, as viewed in Fig. 2, in a clockwise direction will be prevented by the engagement of the arm 24 of the bracket 20 and the arm 26 of the bracket 18. Further, if both of the end panels 11 are warped so that the bottoms of both panels tend to be displaced out of alignment with the door opening, the firm engagement of the several arms of the brackets will maintain the doors in alignment with the door opening.

With the brackets adjusted, as described, during a subsequent closing of the door, the end panels will be brought back into the aligned position of Fig. 2 by engagement of the brackets 18 and 20. As shown in Fig. 4 with one of the doors closed and in alignment with the door opening, and with the end panel of the other door partly open and having its bottom edge warped out of alignment with the door opening, full closing movement of the warped end panel will result in the inwardly extending arm 26 of the bracket 20, being slidably engaged by the outwardly extending arm 24 of the bracket 18 to cam the lower edge of the warped panel into alignment with the door opening as the brackets are brought into the lapping engagement shown in Fig. 2. As should be apparent, if both end panels are warped out of alignment with the door opening, the outwardly extending arm 24 of each bracket may slidably engage the inwardly extending arm 26 of the other bracket to cam both end panels into alignment with the door opening during the final closing movement of the door.

The angles at which the arms of the bracket extend relative to the base should be approximately equal and should be small enough to provide proper retention of

the bottoms of the doors in the aligned position when the doors are closed and further should be large enough to provide correction of a substantial warping of the doors. It is desired that the arms 24 be sufficiently short so as not to provide an obstacle to a person passing through the door, and therefore, for a given projection of the arms 24, if the angle of the arms is too small the amount of warpage correction will be reduced, although the ability to hold the doors aligned when closed will be increased. On the other hand, if the angle of the arms is too great the ability of the brackets to hold the doors aligned when closed is reduced while the warpage correction is increased. In the practice of the invention, it has been found that with the arms extending at an angle of approximately 45° to the base, the best compromise in warpage correction and holding force is realized while the projection of the arm 24 may be maintained sufficiently small.

I claim:

1. A pair of complementary brackets for aligning the lower free edge of an end panel of a folding door with the side edge of a door opening, said brackets each comprising a substantially flat base, a guide arm extending outwardly from one edge of the base at an acute angle to the plane of the base, and a second guide arm vertically spaced relative to the first arm and extending angularly of the first arm and inwardly from said one edge at an angle to the base corresponding generally to that of the first arm, and means on each base for respectively mounting the brackets in inverse relation on the face of the panel and on a member forming a side of a door opening whereby when the door is moved to closed position the second arm of one bracket is brought into sliding engagement with the first arm of the other bracket to cam the lower edge of the panel into aligned position and whereby the several arms will hold said lower edge in such aligned position.

2. A pair of complementary brackets for aligning the lower free edge of an end panel of a folding door with

10

the side edge of a door opening, said brackets each comprising a substantially flat base, a flat guide arm extending outwardly from one edge of the base at an acute angle to the plane of the base, and a second flat guide arm vertically spaced relative to the first arm and extending angularly of the first arm and inwardly from said one edge at an angle to the base corresponding generally to that of the first arm, said second arm being substantially shorter than the first arm and means on each base for respectively mounting the brackets in inverse relation on the face of the panel and on a member forming a side of a door opening whereby when the door is moved to closed position the second arm of one bracket is brought into sliding engagement with the first arm of the other bracket to cam the lower edge of the panel into aligned position and whereby the several arms will hold said lower edge in such aligned position.

3. A pair of complementary brackets for aligning the lower free edge of an end panel of a folding door with the side edge of a door opening, said brackets each comprising a substantially flat base, a guide arm extending outwardly at an angle of approximately 45° from one edge of the base, and a second guide arm vertically spaced relative to the first arm and extending inwardly from said one edge at approximately a right angle to the first arm, and means on each base for respectively mounting the brackets in inverse relation on the face of the panel and on a member forming a side of a door opening whereby when the door is moved to closed position the second arm of one bracket is brought into sliding engagement with the first arm of the other bracket to cam the lower edge of the panel into aligned position and whereby the several arms will hold said lower edge in such aligned position.
